UNITED STATES PATENT OFFICE.

CLARA E. SLENKER, OF BEAVER FALLS, PENNSYLVANIA, ADMINISTRATRIX OF FREDERICK J. SLENKER, DECEASED.

METALLIC RAILWAY TIE AND FASTENING.

No. 892,094.

Specification of Letters Patent.

Patented June 30, 1908.

Application filed April 29, 1907. Serial No. 370,813.

To all whom it may concern:

Be it known that FREDERICK J. SLENKER, late of Beaver Falls, Beaver county, Pennsylvania, invented a new and useful Metallic 5 Railway Tie and Fastening, of which the following is a full, clear, and exact description, reference being had to the accompanying drawings, forming part of this specification, in which—

10 Figure 1 is a plan view of a metallic railway tie and rail fastening embodying the invention; Fig. 2 is a cross-section on the line II—II of Fig. 1; Fig. 3 is an end view of the same, showing a modified form of clamp; and 15 Fig. 4 is a longitudinal section of a portion of the tie and fastening of Fig. 3.

This invention is designed to provide an improved metallic railway tie having means of simple and positive character for securing 20 the rails thereto, and which will permit the rails to be readily and easily adjusted to any desired gage.

With this object in view the invention consists in a metallic railway tie and rail fastening having certain novel features of construction, arrangement and combination of parts, 25 all substantially as hereinafter described.

Referring to the accompanying drawings, the numeral 2 designates the body portion of 30 the improved tie which is preferably a casting of steel or iron of hollow or box form, with a longitudinal slot or opening 3 in its top extending from end to end thereof, and forming the separated top flanges 4. The 35 inner edge portions of these flanges are formed on their upper surfaces with a series of teeth 5. These teeth preferably extend the entire length of the tie, so that the same tie can be used where several rails would 40 cross it, as in yards, at frogs, etc., although they may be provided at each end portion only. The body of the tie is also preferably provided with the lateral vertical ribs or projections 6, and with transverse bottom pro- 45 jections 6' which serve as anchoring or resisting means to prevent movement of the tie in the direction of the rails or transversely of the track.

7 designates the rails which are seated on 50 the top flanges 4 of the tie, and are secured thereto by means of the clamps or clips 7' which consist of small blocks arranged to fit over the bottom flanges of the rails and provided with teeth 8 on their under sides which

are adapted to engage with the teeth 5, and thereby hold the clamps securely against movement. They are locked in place by means of the nuts 9 engaging the threaded bolts 9', said nuts having a bearing against the under side of the flanges 4, in the manner shown in Fig. 2. By loosening these nuts, the rails can be readily moved nearer together or farther apart, and the clamps then secured in their new adjustment.

In order to give greater resiliency, seats or 65 depressions 4^a are preferably formed in the top flanges 4 in which are placed strips 8 of wood, rubber, or other more or less yielding material, upon which the bases of the rails are seated.

70 The clamps or clips may be of various forms; thus in Figs. 3 and 4, instead of securing them by means of nuts, the depending portion which passes through the slot 3 is provided with a pivoted locking dog 10 75 which is arranged to be swung transversely to engage the under side of the flanges 4, in the manner shown. This dog is held in position by means of a locking arm or lever 11 which is pivoted to the clamp at 12 and has 80 a recess 13 which fits over the dog, in the manner shown in Fig. 4. One edge of the dog is preferably beveled, as shown at 14, so that as the lever is moved into and out of its locking position, its engagement with this 85 bevel edge will throw or partially throw the dog 10 into and out of its transverse locking position. This form of clamp is provided with teeth 8^a for engagement with the teeth 5 of the tie, in the same manner as the clamp 90 shown in Figs. 1 and 2, and permits the same facility for rail adjustment.

95 The bottom of the interior of the tie is preferably inclined downwardly from the center towards each end, so that the ties will readily drain themselves. The countersunk heads of the bolts 9' are also preferably protected by means of pivoted cap plates 9^b.

100 The advantages of this invention result from the novel form of the tie described, whereby it can be cast in a mold and which gives it a broad bearing upon the track bed, substantially equal to that of the ordinary wooden tie. The provision of the lateral and bottom ribs or projections effectually prevents movement or creeping of the tie, while the manner in which the clamps are engaged 105 with the tie insures the rails being held in

place, no matter at what angle they may cross the tie, while at the same time their adjustment is made easy.

Other forms of clamps may be employed, 5 and various changes may be made in the details of construction without departing from the spirit and scope of the invention.

What is claimed is:—

1. A metallic railway tie of hollow box 10 form having a longitudinal slot or opening in its top provided with teeth or projections at its edges said teeth or projections extending throughout a major portion at least of the length of the tie; substantially as described.

15 2. A metallic railway tie, of hollow-box form, closed at the bottom and having a longitudinal slot in its top wall throughout the length of the tie, and teeth or projections adjacent to each edge of the slot for a major 20 portion at least of its length; substantially as described.

25 3. A metallic railway tie of hollow box form closed at the bottom having a longitudinal slot extending through the length of its top, and also having teeth or projections at each edge of the slot, rail clamps arranged to engage the bases of the rails, and having

teeth or projections adapted to engage the teeth or projections of the tie, and means for locking said clamps; substantially as described. 30

4. A metallic railway tie having a longitudinal slot in its top and having teeth or projections on its upper surface adjacent to the edges of the slot, a rail clamp adapted to engage the base flange of a rail, and having corresponding teeth or projections on its under surface, said clamp also having a depending portion arranged to slide in said slot, and means for locking the clamp; substantially 35 40 as described.

5. A metallic railway tie having longitudinal depressions formed in its upper surface, and resilient rail-seating members in said depressions; substantially as described. 45

In testimony whereof I have hereunto set my hand.

CLARA E. SLENKER,
Administratrix of Frederick J. Slenker, deceased.
